UNITED STATES PATENT OFFICE

149,908

DESIGN FOR A SOAP DISH

Lloyd Sahley, Cleveland, Ohio

Application November 6, 1946, Serial No. 134,539

Term of patent 14 years

(Cl. D4—3)

To all whom it may concern:

Be it known that I, Lloyd Sahley, a citizen of the United States and resident of Cleveland, Cuyahoga County, Ohio, have invented a new, original, and ornamental Design for a Soap Dish, of which the following is a specification, reference being had to the accompanying drawing, forming a part thereof.

The figure is a perspective view of a soap dish, showing my new design, the suspending chains being conventionally indicated in dotted lines, for simplicity of illustration.

I claim:

The ornamental design for a soap dish, as shown and described.

LLOYD SAHLEY.
